UNITED STATES PATENT OFFICE.

EDWARD H. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,082,537.

Specification of Letters Patent.

Patented Dec. 30, 1913.

Application filed April 16, 1909. Serial No. 490,301.

To all whom it may concern:

Be it known that I, EDWARD H. LORENZ, a citizen of the United States, residing at Hartford, in the county of Hartford and State of Connecticut, have invented certain new and useful Improvements in Type-Writing Machines, of which the following is a full, clear, and exact description, such as will enable others skilled in the art to which it appertains to make and use the same.

This invention relates broadly to typewriting machines and more particularly to the escapement mechanism of a machine of a type adapted to effect printing noiselessly.

In typewriting machines as hitherto constructed a large part of the noise incident to the operation thereof has been produced by the clicking of the parts of the escapement mechanism, and one of the objects of my present invention is to provide new and improved mechanism for overcoming this objection and which will render the operation of the escapement mechanism substantially noiseless.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is illustrated two of various possible embodiments of the invention, Figure 1 is a view in plan, showing the preferred form of this escapement; Fig. 2 is a side view thereof; Fig. 3 is an end view looking toward the left of Fig. 1, the escapement wheel and other parts being omitted in the interest of clearness and illustration; Fig. 4 is a sectional view taken on line 4-4 of Fig. 1, looking in the direction of the arrow; Fig. 5 represents several parts shown in Fig. 1 but in another position; Fig. 6 is a sectional view taken on line 6-6 of Fig. 5 looking in the direction of the arrow; Fig. 7 shows the parts illustrated in Fig. 5 in the back-spacing position; Fig. 8 is a sectional view taken on line 8-8 of Fig. 7; Fig. 9 is a view in plan of a different embodiment of my invention; Fig. 10 is a

side view thereof; Fig. 11 is an end view of Fig. 9, with certain parts omitted; Fig. 12 is a sectional view on the line 12-12 of Fig. 9 looking in the direction of the arrow; Fig. 13 shows the parts of Fig. 9, but in another position; Fig. 14 is a sectional view on the line 14-14 of Fig. 13, looking in the direction of the arrow; Fig. 15 illustrates the parts of Fig. 13 in the back-spacing position; Fig. 16 is a sectional view on the line 16-16 of Fig. 15 looking in the direction of the arrow.

Similar reference characters refer to similar parts throughout the several views of the drawings.

Referring now to the drawings, and particularly to the embodiment of my invention illustrated in Figs. 1 to 8, inclusive, 1 represents the frame of the machine carrying the pivot screws 2 upon which the escapement rocker 3 and rocker-shaft 4 oscillate. The fixed dog is represented at 5 attached to the upper part of the escapement rocker 3, and the movable dog 6 is pivoted upon a bushing which is clamped by the screw 7 on the rocker 3, a cap 8 below the screw-head and supported by the bushing serving as a guide for the movable dog. It will be understood that the movable dog 6 is free to oscillate between the guide or cap 8 and the rocker member 3. The movable dog 6, in the present instance, is provided near its tooth portion with an oscillatory cam member 9, said cam member rolling upon a cam surface 10 formed upon the rocker member 3. This cam member is carried by an arm 11 pivotally attached at 12 to the movable dog 6. A coil spring 13 is connected at one end to the cam member at 14, and at the opposite end to a post 15 upon the rocker 3. 16 represents the escapement shaft, and 17 the escapement wheel, a tooth of said wheel normally bearing against the tooth of the movable dog 6, as shown in Fig. 1, the carriage at this point being held in its normal position of rest. In this position the rolling cam 9 rests against the cam surface 10 and, as will be observed, in the present instance the parts are so positioned that a slight space is left between the face of the tooth of the movable dog 6 and the face of the fixed dog 5. (See Figs. 1 and 4.) Having described the construction of this embodiment of my invention, the operation thereof may now be understood.

Upon depressing the rocker 3, the tooth of the movable dog 6 will be released from the tooth 18 of the escapement wheel, allowing the tooth 19 to drop upon the fixed dog 5, as shown in Figs. 5 and 6. The movable dog, upon release, jumps forward to the position shown in these two figures, being impelled to that position by means of the spring 13 which oscillates the rolling cam 9 from the position shown in Fig. 1 to that shown in Fig. 5, the curved surface of the cam 9 rolling upon the curved surface 10 of the rocker. When the rocker is moved upwardly again, the next tooth of the escapement wheel engages the movable dog 6 and drives the same forward against the resistance of the spring 13, which, taken with the rolling cam surfaces 9 and 10, forms a noiseless stop. When it is desired to back-space the carriage, the escapement wheel 17 is pushed rearwardly by any suitable means, from the position shown in Fig. 1 to that shown in Fig. 7, when the movable dog 6 passes in front of the tooth 38. While passing into this position (Fig. 7), the circular cam 9 will be rocked to a greater distance as shown, again tensioning the spring 13. After the tooth 38 of the wheel 7 shall have passed over the tooth of the dog 6 and is in front thereof, the spring 13, cam 9 and dog 6 will assume the positions shown in Fig. 5, and the tooth 38 (Fig. 7) will assume the position there shown by the tooth following tooth 19 in Fig. 5.

In the embodiment of the invention shown in Figs. 9 to 16 inclusive, the fixed dog is shown at 20 attached to the rocker 21. The movable dog is provided with a finger 22 for engaging the teeth of the escapement wheel, and is also provided with a slot 23 which engages with a guide-screw or pin 23. An arm 24 also extends from the movable dog into engagement with a roller 25 supported upon the rocker 21. The movable dog is also provided with a post 26 to which is secured a spring 27, the opposite end of said spring being secured to an extension 28 of an oscillatory curved cam member 29, said cam being provided with a trunnion pivoted to the rocker member. The curved surface 30 of cam 29 bears against the curved surface 30 of the movable dog. In the position shown in Figs. 9, 10 and 12 the carriage is in its normal position of rest, the tooth 31 of the escapement resting against the movable dog 22. In that position, the oscillating cam 29 serves as a stop for the movable dog, in which position the coil spring 27 is under tension. A plate 32 is positioned upon the rocker 21, and this plate, in conjunction with the head of screw 33, holds the movable dog in position upon the rocker member, the dog being free to slide beneath said plate. When the rocker member is moved from the position shown in Figs. 9, 10 and 12 to that shown in Fig. 13, the es-

capement tooth 31 will be released from the finger 22 of the movable dog and will rest upon the fixed dog 20. The movable dog, being released, will jump forward as shown in Figs. 13 and 14, being forced to such position by means of the oscillating cam, the curved surface of which rolls upon the curved surface 30 of the movable dog, such operation being effected by means of the coil spring 27 which draws the cam 29 to the position shown in Fig. 13. When the rocker member 21 is moved in the opposite direction, the next escapement tooth engages with the finger 22 of the movable dog and moves that dog to the position shown in Fig. 9 against the resistance of the spring 27 and the curved cam 29, said cam rolling against the surface 30 and bringing the movable dog and the escapement wheel to a noiseless stop. In order to back-space the escapement wheel 34, that wheel is pushed backwardly, by any suitable means, in the direction of the arrow in Fig. 15 from the position shown in Fig. 9 to that of Fig. 15, until finger 22 of the movable dog passes over or escapes in front of the tooth 41. During that movement, the movable dog will pivot upon the screw 23, the arm 24 of the dog leaving the roller 25 to a slight extent, and the curved surface 30 also leaving the curved surface of the cam 29 a slight extent, enabling the cam and the spring to be drawn into substantially a straight line, as shown in Fig. 15. When the tooth 41 passes in front of the finger 22, the parts will assume the position shown in Fig. 13, the tooth 41, however, being in the position shown of the tooth 35 of that figure.

It will, accordingly, be seen that I have provided mechanism well-adapted to attain, among others, all the ends and objects above enumerated in an exceedingly simple, yet efficient manner.

It will be observed that the entire operation of feeding the part to be spaced, which in the present instance is an escapement wheel, takes place without impact or concussion, and therefore noiselessly, and yet the parts are accurately and positively arrested in the positions to which they are adapted to be moved.

While the proportions of the co-acting cam members may be varied to any different requirements, it is desirable in the embodiments of the invention herein described that one should be substantially twice the diameter of the other. This insures a pure rolling contact between the cam surface and insures against friction which might result if the surface were allowed to slip or slide one upon the other.

When the feed-dog does not move in a straight line, as in Figs. 1 to 8, the arresting of the parts in the proper positions may be secured by varying the proportions

of the cams or changing the location of the pivot of the smaller cam, as shown herein.

As many changes could be made in the above construction and many apparently 5 widely different embodiments of this invention could be made without departing from the scope thereof, it is intended that all matter contained in the above description or shown in the accompanying drawings shall 10 be interpreted as illustrative and not in a limiting sense.

Having described my invention, what I claim as new and desire to secure by Letters Patent is:

15 1. In an escapement for typewriting machines, the combination with the member to be spaced, of a rocker member, a fixed dog secured to one side of said member, a pivotally mounted movable dog secured to the 20 opposite side of said member, and means mounted on the dog for arresting its movement.

2. In escapement mechanism for typewriting machines, coacting escapement devices comprising a rack member, a movable dog adapted to coact therewith, and an eccentric mounted on said dog to silently arrest its movement and the movement of the rack when said rack and dog engage one 30 another.

3. In escapement mechanism for typewriting machines, coacting escapement devices comprising a rack, a pivotally mounted feed dog adapted to coact with the teeth of 35 said rack, an eccentric mounted on said feed dog, and spring means connected with one of said members adapted to hold said feed dog in forward position to engage the teeth of the rack whereby its movement on coacting with the teeth will be silently arrested by means of the spring and eccentric mechanism.

4. In an escapement mechanism, the combination with a member to be spaced, of a 45 movable dog engaging therewith, and pivotally mounted rolling cam means coöperating with said dog and adapted to arrest the movements thereof in both directions.

5. In an escapement mechanism, the combination with the member to be spaced, of a pivotally mounted feed-dog coöperating therewith, and rolling cam means coöperating with said dog to arrest the movements thereof in both directions.

55 6. In an escapement for typewriting machines, the combination with the member to be spaced, of spacing means therefor comprising a vibratory dog holder, a fixed dog on one side thereof, a movable dog carried 60 on the opposite side thereof, and means on one of said dogs for silently arresting the movement of said movable dog at a predetermined point in advance of said fixed dog.

65 7. In an escapement mechanism, the combination with an element adapted to be

spaced, of spacing means therefor comprising a dog-carrying, rocking member having a cam surface and provided with a fixed detaining dog and swinging feed-dog, and a rolling cam member interposed between the movable feed-dog and said rocker member coacting with said cam for arresting the movements of the swinging dog when the same is engaged with the element to be spaced.

8. In an escapement mechanism, the combination with an element to be spaced, of spacing means therefor comprising a dog-carrying member having a cam surface and provided with a fixed detaining dog and a swinging feed-dog, a tooth mounted upon the swinging dog, and means interposed between said tooth and said rocker member and coacting with said cam adapted to arrest the former and the swinging feed-dog 85 when the tooth is engaged with the member to be spaced and moved thereby into substantial alinement with the fixed dog.

9. In an escapement for typewriting machines, the combination with the member to be spaced, of spacing means therefor comprising a vibratory dog holder, a fixed dog secured to one side thereof, a movable dog carried on the opposite side thereof, and cam means on the movable dog for silently 95 arresting the movement of said movable dog at a predetermined point in advance of said fixed dog.

10. In an escapement mechanism, in combination, a member to be spaced, and spacing means therefor comprising a vibratory member having a fixed detaining dog mounted thereon, a movable feed-dog pivotally mounted thereon, said feed-dog being provided with a tooth for engaging the member to be spaced, said vibratory member having a cam surface and a pivotally mounted rolling member connected with said tooth coöperating with the cam surface of said vibratory member to arrest the movements 110 of the feed-dog when the tooth thereof is engaged with the member to be spaced and moved thereby into engagement with the detaining dog, and for returning the movable dog to an intermediate position when the tooth thereof is disengaged from the member to be spaced.

11. In an escapement mechanism for typewriting machines, in combination, a member to be spaced, a vibratory carrier provided with a fixed detaining dog and swinging feed-dog, a tooth for engaging the member to be spaced mounted upon the feed-dog, said vibratory member having a curved cam surface, a member connected with said tooth 125 and having a surface adapted to roll with relation to the cam surface, and adapted to arrest said tooth in substantial alinement with the fixed dog when the same has been engaged with the member to be spaced and 130

4
moved thereby, and a tension spring connected with said rolling member.

12. In an escapement mechanism for typewriting machines, the combination, of a member to be spaced, a rocker member, a feed-dog pivotally mounted thereon adapted normally to rest in an intermediate position but capable of being swung to either side of such position, and rolling cam means interposed between the pivotally mounted feed-dog and said rocker member adapted to arrest the movements of said dog when the same is moved to either side of its normal position, and spring means coöperating with said cam means for arresting the feed-dog in its intermediate position.

13. In an escapement mechanism for typewriting machines, the combination with the member to be spaced, of a rocker member, a pivotally mounted feed-dog carried thereby, a tooth carried by the feed-dog, and rolling cam means connected with said tooth which normally holds the feed-dog in an intermediate position but which is adapted to arrest the said feed-dog and the tooth thereof when the latter has been engaged with the member to be spaced and moved thereby.

14. In an escapement mechanism for typewriting machines, the combination with the member to be spaced, of a vibratory dog-holder, a swinging dog mounted thereon, a tooth mounted upon the feed-dog, and a member having a rolling engagement with the dog-holder adapted to arrest the movements of said tooth and the feed-dog when the former is engaged with the member to be spaced and moved thereby.

15. In an escapement for typewriting machines, the combination with the member to be spaced, of spacing means therefor comprising a vibratory dog holder, a fixed dog secured to one side thereof, a movable dog carried on the opposite side thereof, and spring actuated cam controlled means for arresting the movement of said movable dog at a predetermined point in advance of said fixed dog.

16. In an escapement mechanism for typewriting machines, the combination with the member to be spaced, of spacing means therefor, comprising a vibratory dog-holder, a swinging feed-dog carried thereby having an engaging tooth, a curved cam surface provided on the dog-holder, a rolling cam

member connected with said tooth adapted to roll with relation to the cam surface of the dog-holder and arrest said tooth when the same has been engaged with the member to be spaced and moved thereby, and a spring connected with said rolling member adapted to return said dog and tooth to normal position when the same has been disengaged from the member to be spaced.

17. In an escapement for typewriting machines, the combination with the member to be spaced, of spacing means therefor comprising a vibratory dog holder, a movable dog carried by said dog holder, a cap for holding said movable dog in proper position during its movement and means secured to one side of said rocker member adapted to aid in silently arresting the movement of the movable dog on the other side of said rocker member.

18. In an escapement mechanism, the combination with an escapement wheel, of spacing means therefor comprising a rocking member, a fixed dog and a movable dog thereon, cam means for silently arresting the movable dog slightly in advance of said fixed dog whereby the teeth of the escapement wheel will engage said fixed dog when released from the movable dog and an actuating spring between said cam means and rocker member.

19. In an escapement mechanism, the combination of a vibratory dog carrier, a loosely mounted movable feed-dog carried thereby, said feed-dog being provided with a cam surface, and spring-actuated means coöperating with said cam surface to position said dog.

20. In an escapement mechanism, the combination of a vibratory dog carrier, a loosely mounted, movable feed-dog carried thereby and provided with a cam surface, and a spring-pressed member mounted upon said dog carrier and coöperating with said feed-dog and the cam surface thereof to arrest a movement of the latter in either direction.

In testimony whereof I affix my signature, in the presence of two witnesses.

EDWARD H. LORENZ.
